UNITED STATES PATENT OFFICE.

EMIL R. YOUNG, OF JORDAN, MINNESOTA.

MECHANICAL TOY.

1,109,498.

Specification of Letters Patent. Patented Sept. 1, 1914.

Application filed December 13, 1913. Serial No. 806,627.

To all whom it may concern:

Be it known that I, EMIL R. YOUNG, a citizen of the United States, residing at Jordan, in the county of Scott and State of Minnesota, have invented new and useful Improvements in Mechanical Toys, of which the following is a specification.

This invention is an improved mechanical toy providing a moving figure representing a rabbit, in a hollow stump and two other figures one representing a hunter and the other a dog endeavoring, the one to strike the rabbit with a stick and the other to grab the rabbit, the invention consisting in the construction, combination and arrangement of devices hereinafter described and claimed.

In the accompanying drawing: Figure 1 is partly an elevation and partly a vertical 20 sectional view of a mechanical toy embodying my invention. Fig. 2 is partly a plan and partly a horizontal sectional view of the same. Figs. 3 and 4 are detail sections on the lines *a—a* and *b—b*, respectively, of 25 Fig. 1.

A base casing 1 has a platform 2 provided with a central opening 3 and a representation of a hollow stump 4 around said opening. The stump has oppositely arranged openings 5 and 6. The platform also has oppositely arranged openings 7 and 8. A shaft 9 is mounted in the center of the casing and stump and has a master gear 10 loose thereon and arranged just below the 35 stump and forming the bottom thereof. A figure as of a rabbit 11 is mounted on the master gear for movement therewith around in the stump. The shaft has a coiled spring 12 wound thereon and one end of the spring 40 is attached to the master gear. A ratchet wheel 13 is fastened to the shaft and is engaged by a spring pressed pawl 14 carried by the master gear. The lower end of the shaft may be engaged by a key to enable the 45 spring to be wound, the spring when unwinding serving to rotate the master gear as will be understood. A secondary gear 15 is mounted on a suitable axle 16 and arranged under the opening 7 and to engage 50 the master gear. This gear 15 has a toothless segment 18 to permit the master gear to turn to a certain extent independently thereof and also has a tappet pin 19 which is engaged by a tappet arm 20 of the master 55 gear so that after the master gear makes a partial rotation independently of the sec-

ondary gear said pin and arm reengage the secondary gear with the master gear. A figure 21, as of a dog has its body pivoted to hind legs and front legs and has a weighted head and a flexible tail. The legs are also pivotally mounted on the platform, the front legs having a downwardly extending tappet arm 21^a which projects through the opening 7. This figure is arranged opposite the opening 5 and is adapted to move toward and from said opening. The weighted head throws the figure forwardly by gravity and the secondary gear 15 has a tappet element 22 which by engagement with the tappet arm 21^a of the front feet moves the dog back just before the gear 15 stops. A similar secondary gear 23 is arranged for rotation on an axle 24 and under the opening 8 and has a toothless segment 25 and a tappet pin 26, the latter being adapted also to be engaged by the tappet arm 20 so that the gear 15 will be turning when the gear 23 is at rest. A figure 27 representing a man in a recumbent position is arranged opposite the opening 6 and has a pivoted arm 28 which carries a stick 29. This arm also has a tappet 30 which may be engaged by a tappet 31 of the gear 23.

When the toy is in operation the rabbit 85 being carried around by the master gear 10 appears successively opposite the openings 5 and 6. The figure of the dog and the weighted arm of the man or hunter move downwardly and forwardly by gravity 90 toward the openings. The secondary gears are so timed with respect to the master gear that their tappets engage the tappets of the figures and move the latter from the openings immediately after the figure of the 95 rabbit appears at the opening so that the toy makes it appear that the dog and the man make ineffectual efforts to get at the rabbit, owing to the fact that the secondary gears lag for an instant after each rotation 100 while the master gear revolves continuously.

Having thus described my invention, I claim:

1. In a toy the combination of a master gear, having a tappet arm, a figure carried by said gear, a secondary gear for engagement by the master gear and having a toothless segment to permit partial independent rotation of the master gear and also having a tappet pin for engagement by the tappet arm of the master gear to cause the sec-

ondary gear to reengage the master gear after the latter has made partial independent rotation and a second figure having a moving part and means to cause said moving part to be actuated by said secondary gear.

2. In a toy, a master gear having a tappet arm, a figure carried by said gear, a plurality of secondary gears for engagement by the master gear and each having a toothless 10 segment and also having a tappet pin for engagement by the tappet arm of the master

gears and a plurality of figures each having a moving part, and means to cause the secondary gears to actuate the moving parts of the last-named figures.

In testimony whereof I affix my signature in presence of two witnesses.

EMIL R. YOUNG.
